UNITED STATES PATENT OFFICE.

GEORGE W. SCHAUERTE, OF ALTON, ILLINOIS, ASSIGNEE, BY MESNE ASSIGNMENTS,
TO WESTERN CARTRIDGE COMPANY, OF EAST ALTON, ILLINOIS, A CORPORATION
OF DELAWARE.

BASE WAD.

Application filed May 6, 1922. Serial No. 553,085.

To all whom it may concern:

Be it known that I, GEORGE W. SCHAUERTE, a citizen of the United States, and residing at Alton, county of Madison, Illinois, have invented the new and useful Improvement in Base Wads, of which the following is a specification.

This invention relates to cartridges for fire arms, and more particularly to paper shell cartridges, such as are used in shot guns and similar arms.

The ordinary paper tube cartridge as manufactured at present is provided with a tubular metal base in which the percussion cap is mounted. The paper tube is mounted within the tubular portion of this base and a so-called base wad consisting usually of a heavy paper plug is mounted within the base of the tube to support the same on the inside, while the tubular portion of the metal base is crimped or otherwise secured to the paper tube. The base wad thus forms a backing for the tube so that the crimping operation will provide a secure fastening.

Great difficulty is often experienced with a cartridge of this type on account of the burning of the paper tube by the heat generated upon discharge. The usual experience is that the paper tube is burned partly through along a circumferential line at the terminus of the base wad. The result of such burning is obviously a weakening of the paper tube along such a circumferential line.

The ejecting mechanism of some fire arms is arranged to engage a flange on the metal base so as to draw the cartridge from the barrel. This ejecting mechanism usually engages the base at only one point in its circumference. The result is that the ejecting forces being applied at one point of the rim exerts, in addition to the tension necessary to draw the cartridge from the barrel, a bending movement tending to tilt the base with respect to the tube. This action tends to produce a heavy stress in the paper tube at the weakened portion where the tube has been burned by the discharge. This stress moreover is concentrated at one side of the tube and, therefore, at practically one point of the weakened circumferential line. This results in a tearing action, which starts at a point where the force is first applied and as the tear progresses in both directions along the weakened circumferential line, the point

of resistance to the tearing forces progresses also along that line. It will be evident, therefore, that this arrangement tends to concentrate the tearing force always at that point of the tube where it is weakest to resist tearing. As a result of such combination of forces, it often happens that in the operation of ejecting a cartridge, the base is torn off and the tube left in the barrel. The result of this, particularly with automatic fire arms, is that a new shell will be crowded in upon the tube, ramming in the barrel with the result that the mechanism will jam.

One of the objects of this invention, therefore, is to provide an improved cartridge in which the danger of tearing the tube upon ejection will be obviated.

Another object of this invention is to provide a cartridge in which the necessary burning of the tube upon discharge will be confined to a non-circumferential line or a line of greater extent than the circumference of the tube taken at right angles to the axis thereof.

Another object of this invention is to provide such a cartridge in which the burning action is confined to an undulatory line on the tube.

Another object of this invention is to provide a paper tube cartridge arranged so that the burning will take place in such a way that the forces imposed by the ejecting action will not be concentrated at the burned portion of the tube.

Further objects will appear from the detail description taken in connection with the accompanying drawing, in which:

Figure 1 represents a cross sectional view of a cartridge shell embodying this invention; and

Figure 2 is a perspective detail of Figure 1 showing the structure of the base and the base wad.

Referring to the accompanying drawing, 1 designates a tubular metallic base. This is usually provided at the center with an inverted flange 2 adapted to receive the percussion cap. The paper tube 3 is mounted within the tubular base 1 and reenforced or backed by the base wad 4. The tube 1 may then be crimped or knurled as indicated at 5, so as to secure the tube 3 in place.

The upper edge of the base wad 4 is provided with an undulatory contour as

shown at 6. The base wad may further be formed as indicated at 7 to receive the percussion cap 9, and may be enlarged as indicated at 8 to permit the gases from the cap 5 to reach the charge.

Upon ignition of the charge, an intensely high temperature flame is usually generated within the space 8 and immediately forward thereof. The result is that the paper 10 tube 3 is often burned where not protected by the base wad 4. With this construction the line of burning of the tube 3 is confined to an undulatory line following the contour of the edge 6. It may be seen that 15 with this construction the burning cannot take place along a simple circumferential line.

The result of confining the burning to an undulatory line or a non-circumferential 20 line is to vary the direction of the line of burning in relation to the direction of the force applied during the ejecting action. If a tear should be started by the ejecting forces, it will be noted that the direction 25 of the tear must change materially as the tear progresses. The result is that the relative direction of the weakened surface and the applied force will change and the force will no longer be applied directly across 30 the tear as would be the case if the burning were confined to a simple circumferential line. It is well known, of course, that any material will offer a greater resistance to a force applied along the tear than to one 35 applied transversely thereto. By serrating or scalloping the end of the wad, the tube is exposed, at its junction with the base wad, along an extended line, which is greater than its internal circumference; accordingly, in-

cidental scoring of the tube is directed along 40 and restricted to this line. Moreover it is found that by this serrating or scalloping the scoring is mainly restricted to the valleys, so that the scoring is mainly at spaced 45 points and not along a continuous line; this still further obviates fracture of the tube. It will thus be evident that in a cartridge constructed according to this invention, the liability to tear upon ejection will be obviated. 50

It is obvious that various changes may be made in details of construction without departing from the spirit of this invention; it is, therefore, to be understood that this invention is not to be limited to the specific 55 details shown and described.

Having thus described the invention, what is claimed is:

1. A paper tube cartridge having a base wad with its end formed to describe a line 60 of juncture with the tube of greater length than the internal circumference of the tube.
2. A paper tube cartridge having a base wad having its end formed to provide an undulating line of juncture with the tube. 65
3. A paper tube cartridge having a base wad, the end of which is serrated.
4. A paper tube cartridge having a base wad whose end is formed to direct incidental scoring of the tube along a line 70 greater than its internal circumference.
5. A paper tube cartridge having a base wad whose end is formed to restrict incidental scoring of the tube at spaced points.

In testimony whereof I affix my signature 75 this 15th day of April, 1922.

GEORGE W. SCHAUERTE.
